A. H. McCarty

BY *Benj. S. Webster*
ATTORNEY

UNITED STATES PATENT OFFICE.

ALLEN H. McCARTY, OF STOCKTON, CALIFORNIA.

RAIL-CONNECTING DEVICE.

Application filed April 26, 1926. Serial No. 104,573.

This invention relates to improvements in means for connecting the adjacent ends of railway rails together; my principal object being to provide a device for the purpose which takes the place of the usual fish plate and which positively prevents any lateral tipping and displacement of the rails relative to each other at their ends.

While my connecting device is suitable for use on any railroad, it is particularly intended to be used in connection with light mining, industrial, and contractor's railroads.

Such railways are frequently carelessly laid and no great care is taken to insure a level road bed, rigidity of the ties, or to provide properly secure connections between the rails and the ties or the rails with each other. The result is that the rails frequently cant relative to adjacent rails at their ends, causing the derailment of the rolling stock, with the accompanying damage and loss of time, if nothing worse.

With my improved rail connecting means on the other hand, while it is not necessary to take more time or care in laying the rails than is done at present, the rail-ends are positively prevented from lateral movement relative to each other, and if one rail tips or cant sideways the adjacent rail must move correspondingly, and the wheel engaging edges of the rails remain in alinement at all times.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Fig. 1 is a perspective view of my improved connecting device as applied to a pair of ordinary rails.

Fig. 2 is a similar view of the device detached.

Referring now more particularly to the characters of reference on the drawings, the

numeral 1 denotes the head of a rail of ordinary shape, the rail also having a vertical web 2 and a base flange 3.

My improved rail connecting device comprises a short rail-head portion 4 to project between the adjacent ends of two rails and to aline with the heads thereof. Projecting from both ends of the head 4 and formed integral therewith are side plates 5. These plates are arranged to fit snugly between the heads and base flanges of the rails, and are spaced transversely to snugly receive the webs 2 therebetween. The plates 5 have outwardly projecting flanges 6 along their lower edges to extend at least to the edge of the base flanges 3, and they may overhang said base flanges if desired. This allows the tie spikes to engage the connecting device in common with the rail flanges.

Between the rails the connecting device is provided with a base flange 7 horizontally alined with the flanges 3, so that said flange 7 and the adjacent portions of the flanges 3 of the rails may rest in common on a tie 8 without throwing any strain on the side plates 5.

The plates 5 are provided with longitudinally spaced orifices 9 to aline with the usual holes in the rails, in order that bolts 10 may be applied to fasten the opposed plates and the rail webs together.

It will therefore be seen that owing to the rigid and unitary character of the side webs engaging flanges it will be impossible for one rail to tip or cant without pulling the adjacent rail sideways also. The side edges of the rails and the intermediate head 4 are therefore always in proper alinement with each other.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what

I claim as new and useful and desire to secure by Letters Patent is:

A rail connection member comprising a rail head portion to aline with and be disposed between the heads of adjacent rails, transversely spaced side plates formed with the head portion and projecting beyond the same to extend along the rail on both sides of the web, said plates being orificed to receive bolts to pass through the rail,

flanges projecting outwardly from the side plates all along the same to and substantially flush with the outer edges of the base flanges of the rail and superimposed thereon, and a base portion formed with the head portion and flanges and disposed to lie in vertical alinement with the head and in horizontal alinement with the rail base-flanges.

In testimony whereof I affix my signature.

ALLEN H. McCARTY.
